Primary Examiner — Robert M Spear*Assistant Examiner* — Kendra L Hamilton(74) *Attorney, Agent, or Firm* — Meunier Carlin & Curfman LLC(57) **CLAIM**

The ornamental design for a vehicle occupant monitor, as shown and described.

DESCRIPTION

FIG. 1 is a front perspective view of a vehicle occupant monitor, showing my new design.

FIG. 2 is a front elevation view of the vehicle occupant monitor shown in FIG. 1.

FIG. 3 is a rear elevation view of the vehicle occupant monitor shown in FIG. 1.

FIG. 4 is a right side view of the vehicle occupant monitor shown in FIG. 1.

FIG. 5 is a left side view of the vehicle occupant monitor shown in FIG. 1.

FIG. 6 is a top plan view of the vehicle occupant monitor shown in FIG. 1; and,

FIG. 7 is a bottom plan view of the vehicle occupant monitor shown in FIG. 1.

In the drawings, the broken lines depict environmental subject matter only and form no part of the claimed design.
